UNITED STATES PATENT OFFICE

2,549,330

PHOTOGRAPHIC LIGHT UNIT

Edward B. Noel, Cleveland Heights, Ohio, assignor to General Electric Company, a corporation of New York

Application April 15, 1947, Serial No. 741,632

6 Claims. (Cl. 240—1.3)

1

My invention relates to lighting units for photography and is of particular interest in connection with such units comprising two lamps assembled so as to have a common light center. Units of this type are available commercially and comprise an incandescent lamp to furnish light on the subject before the photograph is taken and an electric discharge lamp which emits an intense flash of actinic light by which the photograph may be taken. The discharge lamp is in the form of a helically coiled tube and the incandescent lamp is mounted coaxially with the tube and the jacket. A lamp unit of this type is disclosed and claimed in copending application Serial No. 503,068, filed September 20, 1943, by Paul B. Davis and myself which application is assigned to the same assignee as the present application and is now Patent No. 2,469,607, issued May 10, 1949.

In the unit disclosed and claimed in the patent the discharge tube and the incandescent lamp are supported from a base which is attached to the open end of a light transmitting tubular jacket surrounding the two light sources. The base has five contact prongs through which electric power is supplied to the lamps and by which the unit may be mounted on a suitable holder.

An object of my invention is to simplify the structure and increase the safety factor and convenience in use of lighting units including lamp units and holders of the above type. Various features and advantages of the invention will appear from the following description thereof and from the claims.

In the accompanying drawing, Fig. 1 is an elevation, partly in section, of a lighting unit embodying my invention, and Fig. 2 is a bottom view of the holder shown in Fig. 1.

Referring to the drawing, the lighting unit comprises three main members: The holder 1, the incandescent lamp 2 and the discharge lamp unit 3. The latter is made up of a light transmitting tubular jacket 4, an annular base 5 and a helically coiled discharge tube 6 of glass or quartz containing a suitable ionizable atmosphere, such as a filling of xenon, and having a cathode 7 and an anode 8 sealed in its ends. The base 5 is cemented to the open end of the jacket and is provided with contact prongs 9, 10 and 11 to which are attached metal wires 12, 13 and 14, respectively, which form a rigid framework in the form of a cylindrical enclosure for supporting the tube 6 axially within the jacket 4 and through which electrical energy is supplied

2 to the discharge tube. The contact prongs 9, 10 and 11 pass through openings in the annular support plate or disc 15 of the holder 1 and the portions of reduced section thereof are releasably engaged by spring clip type electric contacts 16, 17 and 18, respectively, in registry with the openings and secured to the bottom of the disc 15 (Fig. 2) which consists of electrically insulating material. The holder contacts 16, 17 and 18 are arranged in a circle concentric with a socket 19 mounted in the center opening of the support disc 15. The socket 19 accommodates the bayonet type base 20 of the incandescent lamp 2 which is thus supported by the holder 1 independently of the discharge lamp unit 3 and coaxially with the said unit so that the two light sources, that is, the discharge tube 6 and the axially extending filament in the incandescent lamp 2 have the same light center. In such units, the electrical energy supplied to the discharge tube 6 is at a higher voltage than that supplied to the incandescent lamp 2. The highest voltage is impressed on the lead 14 which is in contact with the discharge tube 6 and, when charged, ionizes the gas in the tube 6 to cause a discharge between the electrodes 7 and 8 which are connected across a condenser through contact prongs 9 and 10. The discharge emits a flash of actinic light of high intensity for photographic purposes. A suitable circuit is disclosed in Patent 2,277,697 to H. E. Grier.

In accordance with my invention, the contact prong 11 for the high voltage lead 14 is spaced a greater angular distance from the prongs 9 and 10 than the angular distance between prongs 9 and 10 for safety purposes. Also, an electrically insulating sleeve 21 surrounds the socket 19 for the incandescent lamp 2 and extends beyond both ends of the socket 19 a sufficient distance to prevent electrical flash-overs between the incandescent lamp socket 19 and the holder contacts 16, 17 and 18 on the one hand and between the current lead wires 12, 13 and 14 of the discharge lamp base 20 or the socket 19 on the other hand. This increases the safety factor of the lighting unit. The upper end of the sleeve 21 extends an appreciable distance beyond the top of the base 20 in the socket 19 and the lower end extends an appreciable distance beyond the two set-screw contacts 22 on the bottom of the socket 19 by which the incandescent lamp 2 may be connected across the terminals of a power source of commercial voltage. A flat piece 23 of electrically insulating material is inter-

posed between the closely spaced contacts 22 to prevent short circuits between them.

The sleeve 21 is held in place on the support disc 15 by its shoulder 24 butting against the electrically insulating annular disc 25 cemented to the disc 15 and by a retainer ring 26 of electrically insulating material which makes a frictional fit with the sleeve 21 and is fastened to the disc 15 by a plurality of bolts one of which, 27, is shown in Fig. 1. Set screws also may be used to secure ring 26 to sleeve 21. The ring 26 increases the length of the path between the contact 11 and the contacts 9 and 10 to decrease the possibility of flashover between these contacts. The disc 25 covers and electrically insulates the top of rivets 28 holding the contacts 16, 17 and 18 on the disc 15. The socket 19 makes a frictional fit with the sleeve 21 and is also held in place by a retractable pin 29 (Fig. 1) extending from its interior into the wall of the sleeve 21.

The supporting structure for the helically coiled envelope of the discharge device, comprises spud wires 30 extending laterally from the current inleads 12 and 13 engaging the adjacent top and bottom coil of the tube 6, and tie wires (not shown) looped around the turns of the tube and secured as by welding, to the inlead 14 serving as the triggering electrode for the discharge tube. The inlead 14 (part only of which is shown in the drawing) extends upward from the contact prong 11 on the base 5, thence across the top of the coiled tube 6 and then downward toward the base 5. The last mentioned part thereof is shown in the drawing. Spring strip braces 31 which are welded to the upper end portions of the inleads 12, 13 and 14 and which engage the enclosing jacket 4 serve to give additional support to the helical tube 6 as disclosed in my copending application Serial No. 716,936, filed December 18, 1946.

What I claim as new and desire to secure by Letters Patent of the United States is:

1. A lighting unit comprising, in combination, a lamp holder provided with a socket for an incandescent lamp base and a plurality of electric contacts arranged around the socket, an incandescent lamp removably mounted in the socket, and a lamp unit comprising an annular base surrounding the socket and provided with electric terminals removably engaging the holder contacts, conductive supports extending upward from said annular base to define a cylindrical enclosure and a helically coiled discharge tube mounted on the supports and within the enclosure and being coaxial with and surrounding the incandescent lamp so that the two light sources of the unit have the same light center.

2. A lighting unit comprising, in combination, a lamp holder provided with a socket for an incandescent lamp base and a plurality of electric contacts arranged in a circle concentric with the socket and an electrically insulating tube surrounding and extending beyond both ends of the socket to insulate the socket and the lamp base from conducting parts of the lighting unit, an incandescent lamp removably mounted in the socket, and a lamp unit comprising an annular base surrounding the socket and the insulating tube and provided with electric terminals removably engaging the holder contacts, conductive supports extending upward from said annular base to define a cylindrical enclosure and a helically coiled discharge tube mounted on the supports and within the enclosure and

being coaxial with and surrounding the incandescent lamp so that the two light sources of the unit have the same light center.

3. A lamp holder comprising an electrically insulating annular support, a socket for an incandescent lamp base mounted in the opening in the support and a plurality of electric contacts mounted in a circle on the support concentric with the socket for engaging electric terminals of an annular lamp base and holding the annular base around said socket, and an electrically insulating sleeve surrounding the socket and extending beyond both its ends to insulate the socket and the base accommodated thereby from the contacts on the support.

4. A lamp holder comprising an electrically insulating annular support plate having openings around its center opening for receiving contact prongs, a socket for an incandescent lamp base mounted in the center opening in the plate with its base-receiving part opening in a direction transverse to the plate and a plurality of electric contacts mounted on the surface of the plate facing away from the direction in which the socket opens and each being in registry with a prong-receiving opening in the plate so as to engage a contact prong inserted through said opening.

5. A lamp holder comprising an electrically insulating annular support, a socket for an incandescent lamp base mounted in the opening in the support and a plurality of electric contacts mounted in a circle on the support concentric with the socket for engaging electric terminals of an annular lamp base and holding the annular base around said socket, and an electrically insulating sleeve surrounding the socket and extending beyond its ends to insulate the socket and the base accommodated thereby from the contacts on the support, said sleeve also being interposed between one and the other of said contacts to increase the insulation therebetween.

6. A lamp holder comprising an electrically insulating annular support plate having openings arranged in a circle concentric with its center opening for receiving contact prongs, a socket for an incandescent lamp base mounted in the center opening of said plate with its base-receiving part opening in a direction transverse to the plate for the reception of a lamp base therein and a plurality of electric contacts mounted on the surface of the plate facing away from the direction in which said socket opens and each being in registry with a prong-receiving opening in the plate so as to engage a contact prong inserted through said opening, an electrically insulating sleeve surrounding said socket, extending beyond both of its ends and interposed between said contacts to insulate the socket and the lamp base received thereby from said contacts and said contacts from each other.
